UNITED STATES PATENT OFFICE.

HENRY DONALD HOPE, OF BIRMINGHAM, ENGLAND.

PIVOT FOR SWINGING CASEMENTS.

1,321,442.

Specification of Letters Patent. Patented Nov. 11, 1919.

Application filed April 4, 1918. Serial No. 226,678.

To all whom it may concern:

Be it known that I, HENRY DONALD HOPE, a subject of the King of Great Britain and Ireland, and residing at 55 Lionel street, 5 Birmingham, in the county of Warwick, England, have invented certain new and useful Improvements Relating to Pivots for Swinging Casements, of which the following is a specification.

10 This invention relates to the pivots or joints between a movable casement and the fixed frame on which it is mounted.

The object of the invention is to provide a joint with large bearing surfaces, giving 15 complete closure between the movable casement and its frame, the parts being of such form that they can be quickly and economically manufactured.

The invention consists in making the joint 20 from a pair of flat bottomed cups which can be pressed from thin sheet metal blanks, the rim of one cup being housed an easy fit inside the other cup. One of the said cups forms the pivot or trunnion, the other cup forms the bush or bearing of the joint. 25 The flat bottoms of the two cups are fastened, by suitable means, to the casement and its fixed frame respectively.

The invention can be applied to casements of wood, iron or steel.

I append drawings illustrating my invention as carried out in one form applied to casements made of standard rolled steel sections.

35 Figure 1 is a section through the axis of the joint, the swinging casement member C being in a position parallel to the fixed frame member F.

Fig. 2 is a section of the fixed frame member F showing the larger cup f in elevation.

40 Fig. 3 is a section of the swinging member at the plane a—a of Fig. 6.

Fig. 4 is a section of the swinging member at the plane b—b of Fig. 6.

45 Fig. 5 is an elevation of the fixed member and its cup attached, looking in the direction of the arrow 1 of Fig. 2.

Fig. 6 is an elevation of the swinging member and its attached cup, looking in the 50 direction of the arrow 2 of Fig. 3.

Fig. 7 is an elevation looking parallel to the plane of the casement, showing the

swinging member in its closed position, that is, parallel to and in close contact with the fixed frame member.

55

Fig. 8 is a similar elevation to that shown in Fig. 7, but with the swinging member at right angles to the fixed frame member.

Fig. 9 is an elevation from the outside of the casement frame looking in the direction 60 of the arrow 3 of Fig. 8.

Fig. 10 is an elevation from the inside of the casement frame looking in the direction of the arrow 4 of Fig. 8.

The fixed frame member F is made up of 65 two similar lengths of standard section as shown at Fig. 2, which are welded together at w (Fig. 5). The swinging member is made up of two separate lengths of slightly different section as illustrated in Figs. 3 70 and 4, which are welded together at w (Fig. 6.)

In carrying my invention into effect as applied to steel casements, the diameter of the larger cup f of the joint is preferably 75 made greater than the depth of the standard sections used for the casement and frame respectively. In a well-known standard section of casement frame fixed member F, two flanges project from one side of the 80 web. At the place where the joint is to be placed the flanges are cut away, by end milling or other suitable operation, to receive the larger cup f of the pair which constitute the joint. The cup may be a force 85 fit in the space so formed, and its flat bottom is fastened to the web of the frame member. The flange of the movable casement member C is cut away in a similar manner but to a slightly larger diameter to 90 give a working clearance for the larger cup, and the smaller cup e is similarly fastened to the web of the member concentrically to the cut-away flange space. The cups may be of steel or iron or non-corrosive 95 metal.

The fastening of the flat bottoms of the cups to the webs of the standard sections may be by means of screws, rivets or welding. In the example illustrated the fastening is effected by rivets r.

My invention can be applied to swinging casements of any angle of swing axis; that is, either horizontal, vertical or inclined.

It will be seen that a casement joint made according to my invention possesses the following advantages:—

- 5 Large bearing surface;
- 5 Complete closure of the joint, leaving no "daylight" space for the entry of air or water, as in the usual forms; and
- 10 Economy in production, no turned parts being required as in the usual forms.
- 10 Having now described my invention, what I claim as new and desire to secure by Letters Patent is:—
- 15 The combination with fixed and swinging members each composed of channeled and flanged sections, cut away at the meeting ends of the sections to leave opposed flat

web portions, of a joint composed of a pair of flat bottomed cups, means for fastening the flat bottom of one cup to the flat web portion of the fixed member, means for 20 fastening the flat bottom of the other cup to the web portion of the swinging member, the cup on the fixed member being larger in diameter than the other cup, and the flanges of the sections forming the swinging member being cut away near the sides of the cup to allow for relative rotation between the cups when one is received within the other substantially as described.

In testimony whereof I have signed my 30 name to this specification.

HENRY DONALD HOPE.

Copies of this patent may be obtained for five cents each, by addressing the "Commissioner of Patents, Washington, D. C."
